UNITED STATES PATENT OFFICE.

JAMES C. FORRESTER, OF NEW YORK, N. Y.

BOTTLE-CAP MANUFACTURE.

1,131,354.

Specification of Letters Patent.

Patented Mar. 9, 1915.

Original application filed January 23, 1913, Serial No. 743,749. Divided and this application filed May 28, 1913. Serial No. 769,532.

To all whom it may concern:

Be it known that I, JAMES C. FORRESTER, a citizen of the United States of America, and residing at New York, in the county of 5 New York and State of New York, have invented new and useful Improvements in Bottle-Cap Manufacture, of which the following is a specification.

My invention relates particularly to a 10 process for assembling the different parts of a bottle cap for instance, the metallic member or "tin" as it is usually called, the sticking material, usually prepared paper, and the closing material, usually cork, the 15 present application being a division of my application #743,749 filed January 23rd, 1913.

The special object is to assemble the tin, paper and cork permanently in one machine, 20 rapidly, securely and efficiently.

Briefly the invention contemplates feeding and heating the tins, inserting the paper, either before, during or after heating, but preferably before heating, driving a cork 25 into a tin, squeezing the parts together to insure complete sticking and then ejecting the finished cap.

In the form of mechanism here illustrated for carrying out the invention, the tins are 30 fed from a rapidly rotated dial onto a transfer belt which delivers them successively to a feeding slide. The prepared paper or other sticking material is placed in the tins in any convenient manner. The slide is 35 heated so as to heat the tins as they are fed along the slide. The heated tins soften the prepared paper. The disks of cork or other suitable closing material are fed intermittently into position above the tins and are 40 driven downward against the tacky paper into the tins by spring pressed plungers, the parts so assembled being thus stuck at the same time. The sticking or sealing papers may be placed in the tins by hand or automatically 45 in any suitable manner at any time prior to the time that the tins are fed under the corks, but preferably before heating the tins. After the plunger drives a cork by a spring pressure into a tin, a mechanical pressure by means of a lever is 50 preferably applied to the plunger to squeeze the cork in the tin. Preferably a number of plungers are carried by a turret which rotates intermittently so that a tin is fed and 55 a cork assembled and stuck at each stroke

of the successively rotating turret plungers. As the turret rotates the plungers are successively lifted by a cam and the completed caps directed from the turret to a belt which carries them to a suitable inspecting 60 table.

Figure 1, is a plan view of the principal parts of a machine for carrying out the improved process of my invention. Fig. 2, is 65 a vertical longitudinal section of the same through the feeding and heating slide. Fig. 3, is a front view of the squeezing device, showing the plunger lifting cam. Fig. 4, is a cross sectional view of the tin feeding and heating chute.

In the machine illustrated, the tins or shells are inspected on a suitable table (not shown) and fed onto a suitable rotating dial 5. From this they are directed by a flange 6 on to a belt 7 which delivers them on to the 70 reciprocating feeding slide 8. The arm 9 which is secured to the outer end of the feeding slide 8 has a roller 10 pressed against the cam 11 for instance, by a spring 12. The cam 11 is on the main drive shaft 12' so that 75 as this shaft rotates, the arm 9 and the slide 8 are reciprocated. The slide 8 has a shoulder 13 for engaging the successive tins to feed them forwardly. A pair of spring 80 pressed plungers 14, 14 serve to prevent the tins from moving backward with the slide on which they rest. As the slide is moved forward the spring pressed plungers 15 are interposed behind the end tin and thus hold 85 and prevent it going back with the slide. 90 As the slide moves back, the end tin is thus held and drops on to the support 16 in front of the rotating turret. This turret has a moving table member 17 adapted to receive the tins which are fed forwardly intermittently 95 from the support 16 as the slide moves forward.

The corks are supplied in a chute 20 and fed forwardly intermittently from the bottom by a feeding slide 21. This slide 21 is 100 operated by an arm 22 pivoted at 23 and which has a roller 24 operating in a groove of the cam 25. This cam is on the shaft 12' and swings the arm 22 backward and forward once at each rotation of the shaft. The cork feeding slide and the tin feeding slide are thus operated synchronously. Each cork is fed into the upper end of the tapering passage 26 immediately above the tins. A paper disk having a sticking composition 110

has been inserted in each tin at a convenient time prior to insertion of the cork.

The tins are heated in the present instance in the feeding chute on the slide 8, the heating being accomplished by means of a burner 28. The bottom of the slide may have a series of openings such as 29 for the heat to more directly pass through to the tins. The chute may also have lateral flanges 30, 30 to confine the heat. The temperature may be regulated as required by the particular necessities of the materials employed and the speed of operation. The hot tin softens the prepared paper so that it is ready to stick the cork the instant the cork is inserted.

The turret is rotated on the shaft 32 intermittently by the action of a pawl 33 connected to the arm 34 of the cam operated lever pivoted at 23, so that the turret is rotated step by step at each feeding stroke of the tins and corks. The turret carries a series of plungers 35 which are guided at their upper ends in a plate 36 and at their lower ends in a plate 37 disposed just above the plate 38 which has the tapering cork passages 26. The lower end of each plunger is suitably shaped to apply a pressure on the cork in the proper manner. Each plunger is pressed downward by a spring 39 which is housed within the upper end of the plunger and the plate 36. Each plunger carries a roller 40 on a stud 41 which stud is vertically guided in the slot 42 so as to prevent the plunger from rotating. A cam 43 is secured at one side of the turret for engaging these rollers. The instant the tin and cork are fed into position in the turret a plunger is held above them by the roller 40 resting on the tip of the cam 43. The turret is prevented from turning backward by another one of the rollers 40 resting in a notch 44 in the cam 43. The turret is stopped in proper position by the yielding stop 45 which intercents the roller 40. As the cork is inserted in the turret, the stop 45 is raised and as the turret is rotated clockwise, the roller 40 drops off to the left from the tip of the cam 43 and striking the cork beneath it drives it into the tin on the table 17 striking a sharp blow. The tapered guide 26 contracts the edge of the cork so that it is uniformly fed into the tin. The lever 46, pivoted at 47 is connected by a pin and slot engagement 48 with a projection 49 from the arm 22 so that as the arm oscillates, the lever 46 is rocked. The lever 46 carries the yielding stop 45, previously referred to, and also has a cam face 50 below its right hand end. The arrangement and proportions of the parts are such that when the roller 40 drops down from the tip of the cam 43, the lever 46 is tilted and rocks its right hand end and cam 50 down onto the roller 40 so as to force the roller

and plunger 39 downward and positively squeeze the cork into the tin. This distributes the sealing and sticking material so that the parts are uniformly united. As the turret rotates, the rollers on the plungers successively engage and are lifted by the right hand end 52 of the cam 43. This raises the plungers and releases the finished caps which are directed outwardly from the turret by the finger 54. They thereupon fall 75 through the opening 55 onto a belt 56 which conveys them out on to an inspecting table, not shown. By this method of assembling the caps may be made rapidly and the parts are securely united. An advantage derived 80 from the invention is that by reason of the particular sequence of operations set out the cork is not injuriously affected by heating because the heat necessary to soften the sticking material has been applied before 85 the cork is inserted in the tin. In other words, the cork is only inserted after the adhesive has been softened and the tin is therefore all ready to receive it. This also permits any gases given off in the heating of 90 the sticking material to escape before the cork is seated in the tin. The cork being unheated sticks more quickly to the prepared paper.

What I claim is:—

1. The process of manufacturing bottle caps, which consists in first heating a tin containing only the adhesive binding material to thereby soften said adhesive material, then driving a cork into firm engagement with the said previously softened adhesive material and then momentarily increasing the pressure between the cork and the tin. 95

2. The improvement in the art of forming bottle caps which includes, placing adhesive disks in the tins, then moving the tins with the adhesive disks therein successively through a heating zone and gradually softening the adhesive, removing the 100 tins one by one from the heating zone, then inserting by pressure a sealing disk into each tin after it leaves the heating zone and maintaining such pressure on the sealing disks while the adhesive is setting. 105

3. The improved art of assembling the parts of a device of the character described which includes forcibly inserting a cork into a tin with interposed adhesive material so as to cause adhesion between the cork 120 and the tin, then momentarily exerting a pressure on the cork in excess of the force employed in inserting said cork so as to force the adhesive material into the pores of the cork, then releasing said excess of 125 pressure so as to relieve excessive tension between the cork and the tin and afterward continuing pressure on the cork sufficient to hold the parts together while the adhesive material is setting. 130

4. The improved art of assembling the parts of a device of the character described which includes heating a tin for softening adhesive material therein, inserting a cork 5 into the tin so as to cause adhesion between the cork and the tin, then momentarily exerting a pressure on the cork in excess of the force employed in inserting said cork so as to force the adhesive material 10 into the pores of the cork, then releasing said excess of pressure so as to relieve excessive tension between the cork and the tin and afterward continuing pressure on the cork sufficient to hold the parts together 15 while the adhesive material is setting.

5. The process of manufacturing bottle caps which consists in heating a tin, then forcing a cooler cork into the previously 20 heated tin with interposed tacky adhesive material between the tin and cork with pressure sufficient to suddenly compress the cork against the tacky adhesive material, and then reducing the pressure to allow 25 the cork to expand somewhat and draw

some of the adhesive into its surface pores and holding the cork in the tin under said reduced pressure while the adhesive is setting whereby tensional stresses in the cork and setting adhesive are relieved during 30 the setting of the adhesive and before the adhesive has finally set.

6. The improved art of assembling the parts of a device of the character described which includes applying a heavy squeezing 35 pressure to a cork within a tin with interposed adhesive material to thereby force the adhesive material into the pores of the cork, then reducing the pressure to relieve excessive tension between the cork and tin, 40 and maintaining a reduced pressure to hold the parts together while the adhesive is setting and finally releasing the pressure after the adhesive has set sufficiently to hold the parts united unaided.
